APPARATUS FOR PRODUCING CAP SCREWS AND THE LIKE

Application filed November 4, 1926. Serial No. 146,089.

This invention relates to apparatus for producing cap screws and the like.

Cap screws as known in the trade ordinarily comprise a hexagonal, filister, flat or round head, a threaded shank and an unthreaded portion between the shank and head which may be termed a shoulder. This shoulder has a diameter equal to the outside or crest diameter of the threaded shank.

According to known practice a blank having a shoulder of final diameter and a shank of smaller diameter is rolled between two threading dies to thread the shank. During this threading operation a burr is formed beyond the final turn of the thread and this burr is then rolled down to shoulder diameter by means of planishing blocks.

Apparatus for thread rolling as heretofore known includes vertically mounted threading dies having, above the serrated portions, plane surfaces corresponding to the shoulder of the blank. These surfaces are so dimensioned that the blanks can be suspended from the edges of the die blocks to properly position them for the thread-rolling operation. In the case of ordinary commercial cap screws, the shoulder for a given size screw has a given length but the total length varies in accordance with commercial requirements. In the case of special standards required by the trade, however, the thread length for a screw of given diameter is constant so that the shoulder length varies with the total length.

It is an object of the present invention to provide improved apparatus capable of effectively and economically producing cap screws by the thread-rolling method.

It is a further object of the invention to provide apparatus of the type mentioned for effectively and economically producing cap screws having various shoulder lengths.

With these general objects, and others, in view, the invention consists in the features, combinations, details of construction and arrangements of parts which will first be described in connection with the accompanying drawings and then pointed out particularly in the claims.

In the drawings—

Figure 1 is a top plan view of apparatus for

producing cap screws constructed in accordance with the invention;

Figure 15 is an edge view thereof showing both dies and the cap screw in various positions;

Figure 16 is an end view of the die and positioning and planishing block shown in Fig. 14, mounted in the apparatus of Figs. 1 and 2; and,

Figures 17 and 18 are perspective views of various forms of positioning and planishing dies.

Referring to the drawings, Fig. 13 illustrates one example of a finished cap screw 95 comprising a shank having a threaded portion 22, an unthreaded shoulder 23, and a head 21. The apparatus hereinafter described is capable of producing such cap screws, having shoulders of true diameter and of proper finish and in which the threads terminate 100

regularly and definitely at the shoulders, the screws as a whole approximating, in appearance and strength, a cut-thread product.

According to the present invention, briefly stated, a blank is so formed and the blank is so threaded that the final turn of the thread adjacent to the shank has full crest diameter. Beyond the final turn of the thread the metal of the blank is upset in the form of a ridge or burr which, after threading, is removed. And at some stage in the procedure the shoulder is machined to size. In carrying out the invention according to what is now considered the best plan of operation, the shoulder is machined before die-rolling, and the burr is worked into a prolongation of the shoulder to carry the shoulder down to a thread turn of full outside diameter.

In carrying out the invention along the lines stated, the finished product referred to may be formed from a rough blank such as is shown, for example, in Fig. 10. This blank has an unfinished round head 21^a, a shank 22^a, and a rough finished shoulder 23^a which is somewhat oversize as to diameter and undersize as to length. Between the shank and shoulder is a bevel 24, hereinafter more fully referred to. This blank may be formed in any suitable manner, as by forging from round stock in a heading machine. The head 21^a is finished, as by milling or die-cutting, to form the desired head. Fig. 13 shows a filister head but the head may be polygonal, flat or round, the head finishing being a well-known operation and forming no part of the present invention. The shoulder 23^a is machined, i. e. cut, to true final diameter, thus giving it the desired finish and accurate size. This machining of the shoulder may conveniently be done when the head is machined to trim the top and bottom thereof.

The above described operations provide what may be termed an intermediate blank, such as illustrated in Fig. 11. This intermediate blank has a finished head 21^b, a shank 22^b and a shoulder 23^b which is finished to the final diameter but is somewhat undersize as to length. The total length of the intermediate blank is approximately the length of the screw when finished. The difference in diameter between shoulder and shank equals the amount by which the metal of the shank will be thrown outwardly in rolling the thread. Between shoulder and shank is a bevel 24^b. The angle of the bevel and the deficiency in stem length are hereinafter referred to.

This intermediate blank is die-rolled to thread the same, the threading extending along the shank and part way up the bevel, the extent being hereinafter more fully referred to. This die-rolling operation is such as to upset the rolled metal into the form of a thread. The metal of the blank is caused to flow outwardly to form the thread crest, the

outside diameter of which is approximately that of the finished shoulder. During the rolling operation described, only that part of the blank that is to be threaded is die-rolled, the shoulder and upper part of the bevel being left free. During threading, some of the metal of the bevel of the blank is caused to be upset and displaced outwardly into the form of a ridge or burr beyond the final turn of the thread.

Fig. 12 illustrates this stage of the production. The uncompleted screw there shown has a threaded shank 22^c and an unthreaded shoulder 23^c. Beyond the final turn of the thread, adjacent the lower end of the shoulder is a ridge or burr 25 slightly greater in diameter than the shoulder. The shoulder, for the most part, remains unchanged but there may be a slight enlargement of its lower end due to the crowding of the metal in forming the burr. Should this occur it is corrected when the burr is removed, as later described.

The invention in its entirety includes two complementary threading dies between which the blank rolls as the thread is formed. As shown as an example in Figs. 1-7, slidable in upper and lower tracks 31, 32 of a bed block 33 is a slide 34 having a die-carrying portion 35. This latter carries a flat, substantially rectangular die block 36 which rests on a ledge 37 of the carrier 35 and is secured in place by means of clamps 38 and bolts 39. The outer vertical face of the die block has a series of threading teeth 40 hereinafter referred to. To reciprocate the die block 36, in the embodiment here illustrated, secured to the slide 34 is the end of a pitman 41 driven from a rotary disk 42 by a crank pin 43 mounted therein. Disk 42 is connected with a gear 44 meshing with a pinion 45 on a drive shaft 46. This shaft is rotated by a pulley 47 to which power may be applied in any suitable manner. As the drive shaft rotates, the slide 34 is moved back and forth in the bed block, thereby causing endwise reciprocation of the die 36.

Opposite the reciprocating die 36 is a complementary die which, in the present embodiment, is stationary. To this end, as shown, carried by the frame or bed block is an adjustably mounted supporting block 51. This block has a ledge 52 on which is supported a die block 53 held in place by clamps 54 and bolts 55 and arranged on a level with die 36 (Fig. 2). The outer vertical face of the die block 53 is formed with a series of parallel rectilinear teeth 56 running endwise of the block but at an angle to the longitudinal axis thereof. The teeth 40 of die 36 are similarly arranged, the teeth of one die, however, being opposed to the intervening grooves of the other die. As will be understood by those skilled in the art, the angle of the die teeth with respect to the axis of the block, that is,

with respect to the line of travel of the blank, governs the lead of the thread formed. In the present embodiment, the two die blocks are located substantially parallel and so spaced apart that the tooth crests are separated by a distance less than, and the groove bottoms by a distance greater than, the diameter of the shank of the blank to be threaded. That is, the groove bottoms, which determine the thread crests, are spaced apart a distance approximately equal to the diameter of the desired product. The position of die block 36 may be adjusted by the use of shims. Die block 53 may be adjusted by adjustment of the supporting block 51 by means of bolts 57 and by the use of shims. In the embodiment shown, the die blocks are formed with teeth on both faces so that the blocks may be reversed as one set of teeth wears out but, for the purposes of the present description, only one toothed face need be considered. To facilitate the entrance of the blank between the dies, the opposing ends are sloped or rounded off as appears in Fig. 4, giving, in effect, a bell mouth entrance for the blank.

In the apparatus here shown as an example, the ends of the die teeth along the sides of the dies toward the blank head—or what may be termed the trailing ends of the die teeth—are ground or chamfered off at an angle to the plane of the tops of the teeth (Figs. 6, 7 and 8). While one purpose of so chamfering the dies is to prevent the teeth from chipping and breaking off at the trailing ends during threading, such a die construction cooperates conveniently with the bevel of the blank in the formation of the desired product.

With the movable die drawn back to the end of its idle stroke (Fig. 1), a blank is positioned adjacent the opposing ends of the complementary dies. It will be apparent that the blank must be so positioned above the die teeth that the shoulder will be beyond the teeth. There is provided means for fixing the position of the blanks with respect to the die teeth. This may be accomplished, for example, by a pair of complementary ledges associated with the die teeth and on which the blank heads may be suspended, these ledges being so arranged, however, that the blank shoulders are left free during thread rolling. In the embodiment illustrated in Figs. 1-7, the ledges are formed as part of the two die blocks. To this end, die block 36 extends beyond the line of termination of the chamfered teeth so that its top edge forms a ledge 60 for receiving the head of a blank. The die blank 53 is similarly formed to provide a ledge 61. These complementary ledges receive the underside of the head of the blank which is thus suspended between the die blocks. The ledges 60, 61 are spaced from the line of termination of their respective die teeth a distance to cause the blank to

be so positioned with respect to the die teeth that the desired point on the blank comes opposite the line of termination of the teeth. As is known to those skilled in the art, there is a tendency for the blank to jump endwise in the direction of its head when the teeth take hold. Consequently, this jump is allowed for. The amount of jump for a given set of dies being known, the ledges 60, 61 are spaced from the teeth accordingly. The ledges initially position the blank, which then jumps and thereafter it is held in the same relative axial position by the inter-engagement of the die teeth and the formed thread.

Due to the extension of the die blocks 36, 53 to form the ledges 60, 61, the die blocks have plain surfaces 62, 63 that come opposite the shoulder of the blank and part of the bevel. These plain surfaces are so formed that when the die blocks are in position the plain surfaces 62, 63 are spaced apart a distance substantially greater than the diameter of the shoulder of the blank. In terms of one die, its plain surface is located below the plane of the bottom of the die teeth (Figs. 7 and 8). Consequently, during the thread-rolling the shoulder of the blank is left free. In other words, the surfaces 62, 63 play no part in the threading operation except in that the ledges 60, 61 initially position the blanks.

A blank being suspended in position, as above described, the moving die 36 is advanced and the blank is rolled between the two dies. That is, the blank revolves on its own axis and travels along between the dies as the moving die advances. For a half turn of the blank the teeth of die 36 form thread portions in half the surface of the blank and the teeth of die 53 form thread portions in the other half of the blank surface, the die teeth digging into the metal to form the thread grooves and displacing the metal outwardly into the die grooves to form the thread crest. During the next half turn of the blank the half thread portions formed by die 36 are presented to die 53 and the half thread portions formed by die 53 are presented to die 36 for further formation or finishing or both. With the apparatus described, the complete thread is roughly formed during the first half turn or few half turns of the blank, the remainder of the action being in the nature of a finishing or planishing operation. During this threading operation, the chamfered portions of the die teeth, acting on the bevel of the blank, thread part of the same and upset some of the metal into the form of a ridge or burr beyond the final turn of the thread. Fig. 8 illustrates the relation of blank and die after the moving die has progressed far enough to form the thread. The die teeth have dug into the blank to form the thread groove and the metal has been displaced into the die

grooves to form the thread crest. Fig. 8 also illustrates how the chamfered ends of the die teeth have threaded part of the bevel and have upset the metal into a burr 25 beyond the final turn of the thread.

5 The invention in its entirety includes platens for rolling down the burr to stem diameter, these platens being freely separated from and independent of the threading dies. The 10 platens may, for example, also be formed as part of a second die block having a spacing portion and a platen portion. In the exemplification illustrated in Figs. 1-9, there is provided a pair of complementary platen die 15 blocks 72, 73. These are rectangular blocks of the same height as the threading die blocks. The platen die block 72 is mounted alongside of threading die block 36 and the platen die block 73 alongside of threading die 20 block 53. The two platen die blocks are held in their respective die carriers by clamps 74 and 75 like the clamps which hold the threading die blocks and may be adjusted by shims.

At the top of platen die block 73 is a 25 platen 71 (Figs. 3 and 4) formed as a part of the block, being thicker than the remainder of the block. This platen has its front face substantially in the plane of the bottoms of the grooves of the adjacent threading die. In width, i. e., vertical width, the platen extends down to a line substantially below the line of termination of the teeth of the adjacent threading die (Fig. 3). The 30 platen length is sufficient to enable it to act on a blank during one or more revolutions thereof. The remainder of block 73 is a spacing portion. That is, it serves to space the platen portion from the ledge of the die carrier.

40 Die block 72 is an oppositely facing duplicate. That is, it has a platen portion 70 like platen 71 and a spacing portion like that of block 73.

When the two platen die blocks are opposite each other (Fig. 9) the platens 70, 71 are spaced apart a distance substantially equal to the diameter of the blank shoulder.

45 As appears in Fig. 3, when the platen blocks are in place the platens are in line with the plain surfaces 62, 63, but they are wider than the latter by the width of several die teeth. That is, the platens are arranged to come opposite the blank shoulders and several turns of the thread. The platen surfaces are arranged parallel to the plane of the tops of the teeth except that they are 50 slightly sloped off (Fig. 4) at the end toward the die blocks to facilitate entrance of the blanks.

55 As the slide 34 moves across carrier 51, and near the end of the stroke, platen 70 moves across platen 71 and part of the blank is rolled between them (Fig. 9). During the 60 rolling operation the upset metal of burr 25 is rolled down by the platens, the displaced

metal being received by the final turn of the thread. That is, the metal is worked into the shoulder to prolong the same, carrying the shoulder down to a thread turn of full outside diameter. If the shoulder 23° of the partly formed blank is increased in diameter as above referred to, it will have true diameter after the rolling by the platens.

65 Except in positioning the platens, the blocks 72, 73, other than the platen portions 75 play no part in the operation. As the distance separating the faces of the spacing portions of the blocks is greater than the diameter of the blank they obviously do not touch the blanks.

70 Fig. 9 illustrates the relation of the parts near the end of the platen action. The burr 25 has been rolled down, the displaced metal being received by the final turn of the thread and elongating the shoulder, which extends 85 down to a thread turn of full outside diameter.

75 It is considered advisable to have the platens extend downwardly some distance beyond where the burr is encountered. Theoretically 90 the platen surfaces are tangential to the thread crest but if it is found that the platens tend to flatten the thread crest, the platen surfaces may be ground off adjacent the lower edges to avoid this.

80 As the moving die reaches the end of its rolling stroke the blank reaches the end of the stationary die and can drop out, to be collected as desired. The moving die then makes an idle return stroke to initial position, thus completing the cycle of operations 100 for one blank.

85 Referring back to the blank, it is noted that the bevel 24 above referred to need not necessarily be a true bevel. That is, the surface may be frusto-conical or may be slightly rounded. What is desired is a gradual step down from shoulder to shank of such dimension that the dies will upset such a burr as can be worked into the shoulder to prolong 110 the same as described. For convenience, however, the term bevel has been used. The angle of the bevel is not the same for all blanks. Generally speaking, the angle of bevel varies with the diameter of blank and with the 115 depth of thread to be formed. As it is difficult, even with these values known, to fix a standard, it is considered advisable to adopt a given bevel and make a trial run. It has been found that for screws varying in diameter from $1/4''$ to $7/8''$ a suitable range of included bevel angles is from 20° to 30° . This range provides a starting point for a given production run, correction being made, if necessary, after a trial run, as later described. As the difference in shoulder and shank diameter for a given size screw and given dies is fixed, the fixing of the bevel angle, of course, determines the axial length 120 of the bevel.

125 90 130

5 The angle of chamfer of the die teeth varies, generally speaking, with the angle of the bevel. For the above mentioned range of screws, a suitable range of chamfer angle is 25° to 35° . As a starting point for a given run, the die blocks are conveniently formed so that the blank is positioned in rolling to cause the threading to extend about two thirds of the way up the bevel.

10 As an example, the following dimensions and relations have been found suitable for the production of $1/2''$ steel cap screws, all figures being approximate:

Diameter of shank of blank (22), $7/16''$.

15 Diameter of shoulder (after machining) (23), $1/2''$.

Axial length of bevel (24), $5/32''$. (This gives an included bevel angle of about 24° .)

20 Length of shoulder of blank (23), $28/64''$, varying slightly at different points around the circumference of the blank.

Angle of chamfer of die teeth, 30° .

Width of plain surfaces (62, 63) separating teeth from positioning ledges, $13/32''$. (This allows for a blank jump of about $1/8''$.)

25 Diameter of stem and thread crest of screw produced (22), $1/2''$.

Length of shoulder of screw produced (23) at opposite point in circumference, $1/2''$ —
30 $33/64''$.

35 While the shoulder of a given standard size should have the standard length at all points, a slight overlength at some points is immaterial. Variation, such as that above mentioned from a given shoulder length to a slight overlength is also found in cut thread products.

40 As unknown variables, such, for example, as the nature and condition of the stock used, may cause a slight deviation in results, it may be necessary to make a readjustment following a trial run. This may be done, for example, by changing the angle of the bevel of the blank and of the chamfer of the dies, if they are chamfered. Or it may be accomplished by a variation in the axial position of the blank with respect to the die teeth. That is, if the bevel of the blank is too long for a given die, too great a burr is formed. This may be corrected by regrinding the die teeth to change the angle of chamfer, or by using other blanks. If the bevel of the blank is too short for a given die, there is not enough of a burr formed. This may be corrected by new dies, new blanks, or by grinding down the ledges of the dies (60, 61) so as to so position the blanks that the threading extends further up the bevel, more metal thus being upset into the burr.

45 With the apparatus described it is possible to utilize the economical step of threading the blank by die-rolling, at the same time producing a cap screw that has the appearance and strength of a cut-thread product.

50 Further, the parts described permit thread

rolling and planishing in the one passage of the blank and, as threading dies wear out, the same platen blocks may be used, it being necessary to make new dies only. Further, the threading dies shown are economically cut, 70 being plain rectangular blocks.

The embodiment of the invention above described is particularly adaptable to producing the ordinary trade product, above referred to, in which the shoulders have given length for given sizes, the shanks varying in length. A given pair of dies may produce cap screws of any total length up to the width of the dies, the shoulders, however, being necessarily of the same length. 75

80 A further embodiment of the invention is illustrated in Figs. 14-18 inclusive, particularly adaptable to the production of cap screws of the special trade standard above referred to, i. e. in which the screws of a given diameter always have the same thread length regardless of their total length. In the case of these screws, therefore, as the total length varies, the length of the shoulder must vary. 85

90 In the embodiment referred to, provision is made for a variable blank-positioning means for a given threading die. As here shown as an example, a threading die is provided which is generally like the die 36 and is adapted to be mounted by clamps 38 (Fig. 16) in the same machine as above described. Separate blank-positioning blocks of different heights are provided so that when the machine is used to produce a screw of one given length, one size of these blocks is associated with the threading dies and when another length of screw is to be produced another set of blank-positioning blocks is substituted. This permits using the same 95 threading dies to produce screws in which the shoulders have different lengths. The die comprises a generally rectangular block 101 (Figs. 14 and 16) of substantially the same thickness as die 36. The block has width sufficient for the screw to be produced and in length it equals, as shown, the threading die 36 plus the platen block. The die 101 is formed with threading teeth in the same manner as the die 36 and these teeth 100 are similarly chamfered. At the rear end of the die block 101 the top and bottom faces are rabbeted (Fig. 14) for a purpose later described. A complementary die 102 is provided having teeth like die block 53, similarly chamfered. This die block is also rabbeted on its top and bottom faces. In the die blocks 101, 102, the blocks terminate at the chamfers. In other words, the die blocks 105 have no extension along their upper sides 110 forming ledges as in the case of the dies previously described.

115 There are provided platen means for rolling down the burr formed during threading and separate means capable of substitution 120

130

for positioning the blanks with respect to the dies. This may be conveniently accomplished by interchangeable blocks independent of the threading die and combining both positioning ledges and platens.

In Fig. 17 is shown a block 103 provided for this purpose. It is arranged to fit over the threading block as shown in Fig. 14, the rabbeted part of the top face of block 101 engaging the rear enlarged portion of block 103. The two blocks are held in the machine by clamps in the same manner as the die blocks 36 and 53 were held. A similar block 103^a is provided for die 102. It will be seen that the portion of the blocks 103, 103^a to the left of line X—X are blank-positioning portions and that the parts of the blocks to the right of line X—X are planishing portions. As shown in Figs. 1—9 inclusive, the planishing blocks or dies are spaced apart a distance equal to the diameter of the stem so as to roll down the burr formed in threading. On the other hand, the blank-positioning portions of the dies shown in those figures are spaced 25 apart so that during threading they will not make contact with the stem. In other words, the blank-positioning portions and the planishing die are not in the same plane. In the form of block shown in Figs. 14—18, inclusive, it is noted that the faces of the blocks 103, 103^a, are plane surfaces. Consequently, the blocks 103, 103^a, are slightly shifted in the horizontal plane so that their outer faces are inclined to the line of travel of the blank, 35 the pivot point being somewhat adjacent the line X—X (Figs. 14 and 15). Consequently, during the threading operation, the shoulder of the blank will not be engaged by blocks 103, 103^a, to the left of line X—X but, when 40 the blank arrives at a position near the line X—X, the stem will be engaged by the slightly converging faces of the two blocks (to the right of the line X—X), so that the burr will be rolled down as the blank finishes its rolling movement.

It is to be noted that block 103 may also be positioned in a similar manner with respect to the lower face of block 101, the rabbeted part of the latter being provided for proper fitting. This permits of die 101 being used in reverse position.

Figure 15 shows the angular relation between the blocks and the positions of the cap screw 22 during the threading and planishing operations. It will be apparent that the angular shift given the blocks is only slight, the precise angle being found by experiment.

If desired, the blank-positioning and planishing blocks may be made in two parts, the 60 line of division therebetween extending along line X—X. For convenience in manufacture they are preferably formed as one.

In Fig. 18 is shown a block 104 having a blank-positioning portion 105 whose width is 65 different from that of block 103. This block,

and its complement, may be substituted in place of blocks 103, 103^a, when it is desired to alter the overall length of cap screws, while maintaining the length of threaded shank the same. That is, when it is desired to thread a cap screw with a different shoulder length, other blocks, such as blocks 104, are substituted. Blocks 104, for example, being smaller as to vertical height than blocks 103, 103^a, serve to properly position a blank having a shorter shoulder with respect to the die teeth. With this construction cap screws having different shoulder lengths may be threaded in the same dies merely by substituting different positioning blocks.

The operation of the apparatus will be clear from the above without further description.

What is claimed is:

1. In apparatus of the class described, and in combination, two complementary threading dies for threading a cap screw blank and causing, during threading, the formation of a burr on the blank beyond the final turn of the thread, two complementary planishing dies for rolling down said burr and working the metal thereof into the shoulder of the blank to elongate it, said planishing dies being freely separable from the threading dies, and means for causing relative movement between the threading dies and between the planishing dies to cause a blank to roll therebetween.

2. In apparatus of the class described, and in combination, two complementary threading dies for threading a cap screw blank and causing, during threading, the formation of a burr on the blank beyond the final turn of the thread, die carriers in which said dies are mounted, two complementary planishing dies for rolling down said burr and working the metal thereof into the shoulder of the blank to elongate it, said planishing dies being mounted in said die carriers alongside said threading dies but freely separable therefrom, and means for causing relative movement between said die carriers to cause a blank to roll between said dies.

3. In apparatus of the class described, and in combination, two complementary threading dies for threading a cap screw blank and causing, during threading, the formation of a burr on the blank beyond the final turn of the thread, die carriers in which said dies are mounted, two blocks also mounted in said carriers and having a width substantially equal to the width of the threading dies, said blocks having formed thereon two complementary planishing platens for rolling down said burr and working the metal thereof into the shoulder of the blank to elongate it, and means for causing relative movement between said die carriers to cause a blank to roll between said dies.

4. In apparatus of the class described, and in combination, two complementary threading dies for threading a cap screw blank and

causing, during threading, the formation of a burr on the blank beyond the final turn of the thread, die carriers in which said dies are mounted, two complementary planishing platens for rolling down said burr and working the metal thereof into the shoulder of the blank to elongate it, separate die blocks having a width substantially equal to the width of the threading dies and on which said platens are carried and which are also mounted in said carriers, and means for causing relative movement between said die carriers to cause the blank to roll between the said dies.

5. In combination, a die carrier comprising a ledge, a threading die block mounted on said ledge, said block having above its toothed portion a blank-positioning ledge, the surface between the ledge and the termination 10 of the die teeth lying in a plane inside the plane of the bottoms of the die teeth, and a second die block mounted on said ledge at the end of the first die block, the second die block having a planishing platen located substantially in the plane of the bottom of the die teeth of the first die, the platen extending below the terminal line of the die teeth.

6. In combination, means for threading and planishing a cap screw blank comprising in part a block having a series of teeth the ends thereof being chamfered, a second unthreaded block mounted on said first block, and means for positioning said second block so that it forms a blank-positioning ledge 25 with respect to one portion of said first block and a planishing surface with respect to another portion thereof.

7. In an apparatus for forming cap screws having a threaded shank and an unthreaded shoulder, complementary threading dies for forming a thread on blanks rolled therebetween, and separate complementary blocks capacitated to be assembled with said threading dies to form blank-positioning ledges, said blocks, when assembled, having plane surfaces between the ledges and the threading dies lying in a plane below the plane of the bottom of the die teeth, whereby a portion 40 of the blank is left free during rolling, said blocks being readily removable from the dies for substitution of interchangeable blocks of different dimensions, whereby blanks may be positioned in different relative positions with respect to the threading dies.

8. In combination, co-operating threading dies for forming a thread on a blank rolled therebetween, and regulable means for providing blank-positioning ledges, associated 45 with the threading dies, whereby blanks may be positioned at different relative positions with respect to the threading dies.

9. In combination, co-operating threading dies for forming a thread on a blank rolled therebetween, and regulable blocks capaci-

tated to be assembled with said threading dies to form ledges for positioning blanks at predetermined relative positions with respect to the threading dies.

In testimony whereof, I have hereunto set 70 my hand.

GLENN H. WAYNE.
